DESIGN FOR A TOY

Walter R. Braund, Birmingham, Mich., assignor to Bra-Wil-Kee, Inc., Detroit, Mich., a corporation of Michigan

Application November 9, 1944, Serial No. 116,244

Term of patent 3½ years

(Cl. D34—15)

To all whom it may concern:

Be it known that I, Walter R. Braund, a citizen of the United States of America, residing at Birmingham, in the county of Oakland and State of Michigan, have invented a certain new, original, and ornamental Design for Toy, of which the following is a specification, reference being had to the accompanying drawing, forming a part thereof, in which Figure 1 is a perspective view of the toy showing my new design; Figures

2 and 3 are, respectively, a plan view and a side elevation thereof.

The present design comprises as the principal and dominating feature thereof that portion of the toy shown in full lines.

I claim:

The ornamental design for a toy, substantially as shown and described.

WALTER R. BRAUND.
